(57) **CLAIM**

The ornamental design for an earbud, as shown and described.

DESCRIPTION

FIG. 1 is a front, top, and right perspective view of a first embodiment of an earbud showing our new design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines illustrate portions of the earbud and form no part of the claimed design.

The claimed design includes a second embodiment, which is not shown, which is a mirror-image of the embodiment shown in FIGS. 1 through 7.

1 Claim, 2 Drawing Sheets
